UNITED STATES PATENT OFFICE.

WILLIAM M. DWYER, OF CHICAGO, ILLINOIS, ASSIGNOR TO WILLIAM H. MINER, OF CHAZY, NEW YORK.

DRAFT-RIGGING FOR RAILWAY-CARS.

1,309,021.

Specification of Letters Patent.

Patented July 8, 1919.

Application filed December 31, 1915. Serial No. 69,607.

To all whom it may concern:

Be it known that I, WILLIAM M. DWYER, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

This invention relates to improvements in draft riggings for railway cars. And more particularly to that type of railway draft rigging wherein is employed a horizontal 15 yoke or yoke acting member.

Objects of the invention are to provide a draft rigging of the type above indicated and particularly one wherein the gear is readily removable from below, wherein the 20 sills are effectively tied together over a great length and wherein the stop members are so arranged that the section moduli thereof are most advantageously disposed to resist the shocks imposed thereon.

Other objects of the invention are, to provide upper and lower front stop members so arranged that the shocks transmitted thereto are distributed to the sills over a 25 large riveting area; to so arrange the lower front stop member that it may be attached to the lower flanges of channel center sills; to so design the front stop members that insertion and removal of the draw-bar is 30 facilitated and rendered comparatively easy; to so design the rear stop that the rear follower will be placed substantially under compression only, under buff and the usual 35 bending strains eliminated; to so arrange the front stop members that the draw bar will be properly positioned at all times to 40 transmit buffing shocks in the right line and at the same time permit the draw bar to have radial movement while the cars are rounding curves; and to relieve the coupler key 45 from carrying the weight of the coupler or draw bar.

The invention also consists in the improvements in the parts and devices and in the novel combinations of the parts and devices 50 herein shown, described or claimed.

In the drawing forming a part of this specification, Figure 1 is a longitudinal, vertical, central sectional view of a portion of a car showing my improvements in connection therewith. Fig. 2 is a horizontal, sec-

tional view taken substantially on the line 2-2 of Fig. 1. Fig. 3 is a transverse, sectional view taken substantially on the line 3-3 of Fig. 1. And Figs. 4, 5 and 6 are detail, perspective views of the upper front stop, the lower front stop, and the rear stop, respectively.

In said drawing, 10-10 denote channel shaped center sills having their flanges extended outwardly in the usual manner. Secured between and to said sills, at the rear of the draft gear, is the rear stop casting 65 designated generally by the reference A and more particularly hereinafter described, said casting A being secured to the sills as by rivets 11-11, see Fig. 2. Secured to and between said sills, at the ends of the car, is the upper front stop member or casting 70 designated by the reference B, and more particularly hereinafter described. Also secured to the sills and to the lower flanges 75 thereof, is the lower front stop member or casting designated generally by the reference C, and also more particularly described hereinafter. Interposed between the front 80 stop members and the rear stop casting A is a draft gear which, as shown, is of the vertical twin spring type and comprises a front follower 12, rear follower 13, upper spring 14, lower spring 15, and combined spring 85 spacer and limiting stop member 16 interposed between the springs. The draw bar 17 is operatively connected with the gear by means of a U shaped horizontal yoke 18, the latter having the arms thereof provided 90 with elongated slots 19 through which is received the coupler key 20, the latter being also extended through elongated slots 21 in the center sills. The gear is supported by a removable saddle or guide plate 22, the latter being connected by bolts 23 to the lower 95 flanges of the center sills.

Referring now to the rear stop member A, it will be seen that the same is provided on its forward face with an upper, transversely 100 extending shoulder 24, lower, transversely extending shoulder 25, said shoulders forming a horizontally extending groove or recess 26 therebetween and within which is received the transversely extending rear portion of 105 the yoke. The depth of the recess 26 is made such, as clearly appears in Fig. 1, that the inner face of the rear transversely extending portion 27 of the yoke will lie flush with the bearing faces of the shoulders 24 110

and 25. From this it will be seen that the rear follower 13 is provided with an unusually large bearing surface which extends over the greater part of the follower and thereby relieves the same, substantially, of all bending strains and causes it to be placed under compression only, when the gear is operated under buff. The casting A is also provided on each side thereof with longitudinally extending shelves or ledges 28-28, which are flush with the upper face of the shoulder or stop 25, and are adapted to support the horizontal yoke in proper position as clearly appears from Fig. 2. These shelves or ledges 28 are suitably connected with the main body portions of the casting A by vertical flanges 29-29, the latter also limiting the side or lateral movement of the horizontal yoke. For strength, the side walls 30-30 of the casting A by which it is riveted to the sills, are connected by a horizontally extending web 31 at the bottom and a narrower horizontal web 32 at the top, a vertically extending strengthening rib 33 being also employed.

Referring now to the upper front stop member B, the same is shown as comprising a casting having a vertical rear face 34 for the upper portion of the front follower 12 to abut against, a horizontal web 35 which extends entirely across the space between the sills and from the flange 34 forwardly to the vertical end face 36, side flanges 37-37 by which the casting B is riveted to the inner faces of the sills, a relatively narrow transversely extending web 38 at the front, an upper, rearwardly extended riveting flange 39 and a longitudinally extending centrally located strengthening rib 40. At its forward end, the casting B is also provided with upwardly extending side flanges 41-41 to provide additional means for riveting the casting to the sills. As clearly appears from Figs. 1 and 3, the upper flange 39 of the casting is riveted to a plate 42, which is in turn riveted to the top flanges of the center or draft sills. The lower front stop member C, as shown, comprises a rear vertical web or face 43 acting as a shoulder for the front follower 12, a horizontal web portion 44 on which is adapted to ride the lower face of the butt of the draw bar 17, a forwardly and downwardly inclined web 45 which facilitates insertion and removal of the draw bar, as will be apparent, laterally extended riveting flanges 46-46 by which the casting is riveted to the lower flanges of the center sills as by the rivets 47, see Figs. 1, 2 and 3, vertical relatively narrow front web 147, and a strengthening and bracing rib 48 extending longitudinally between the flanges 43 and 147.

At the ends of the center sills, right angled castings 49 are riveted thereto, the latter extending downwardly below the sills and

adapted to have attached thereto a draw bar carry iron 50, the latter having flanges adapted to be bolted to said castings 49 as by bolts 51, and also flanges adapted to be bolted to the lower flanges of the center sills 70 as by bolts 52. For increased strength, angle irons 53 are employed on the outer sides of the center sills to brace the latter and also the castings 49.

From the preceding description, it will 75 be seen that the castings B and C are so designed and located that they afford great strength in resisting the shocks transmitted thereto, and in this connection it will be observed that the upper member B also serves 80 as the dead block for the horn of the coupler in buffering. By arranging the stop members B and C, as shown, the sills are effectively tied together and tendency of the sills to spread or buckle is minimized. By attaching the lower stop member C to the flanges of the center sills, the rivets connecting the same are placed under shear only and relieved of tension and, furthermore, by securing the lower stop member to the sills in the 90 manner shown, even though the center line of draft comes at a point very low on the center sills, nevertheless, relatively shallow center sills may be employed and the stop members effectively applied thereto. Heretofore, it has often been found necessary when the usual types of stop members have been employed, to either add extensions in the form of angle irons to the bottoms of the center sills in order to increase the depth of 100 the center sills and provide means to which the lower portion of the stop castings could be riveted or to extend the castings downwardly below the center sills and use additional metal to strengthen the depending 105 and unbacked portions of the castings. With my arrangement this is entirely eliminated.

In addition to the foregoing, it will be noted that the sills are tied together substantially from the ends thereof to points at the rear end of the rigging, the sills being tied at their end portions by the castings B and C, then for a distance by the tie plate 110 22 and for the remainder of the distance by 115 the casting A. In this way, the sills are adapted to withstand very heavy shocks without danger of spreading or buckling.

Although I have herein shown and described what I now consider the preferred embodiment of my invention, the same is merely illustrative, as it is evident that various changes and modifications may be made in the details of construction without departing from the spirit of the invention 125 and all such changes and modifications are contemplated as come within the scope of the claims appended hereto.

I claim:

1. In a railway draft rigging, the combi- 130

- nation with draft sills flanged at their lower edges, of upper and lower horizontally arranged front stop members for a draft gear, the lower of said stop members having a forwardly and downwardly inclined portion adapted to facilitate the insertion and removal of a drawbar and integral lateral extensions by which it is secured to said flanges.
- 10 2. A front stop member for railway draft riggings, said stop member having a horizontal upper face on which is adapted to ride the butt of a drawbar, a forwardly and downwardly inclined face, a rear vertical shoulder against which a front follower is adapted to abut, and laterally extending horizontal flanges adapted to be secured to the lower flanges of center sills.
3. A front stop member for railway draft riggings, said stop member being arranged 20 to extend from one center sill to the other center sill and be secured thereto, said member having a horizontal upper face near the rear thereof on which is adapted to ride the butt of a drawbar, said member being provided also with a forwardly and downwardly inclined face adapted to facilitate the insertion and removal of a drawbar.
- In witness that I claim the foregoing I have hereunto subscribed my name this 30th 30 day of Dec., 1915.

WILLIAM M. DWYER.
